Patented Oct. 21, 1924.

UNITED STATES PATENT OFFICE.

DAVID J. BISSELL, JR., OF SPOKANE, WASHINGTON, ASSIGNOR TO OTIS AUTOMATIC TRAIN CONTROL INCORPORATED, OF SPOKANE, WASHINGTON, A CORPORATION OF WASHINGTON.

RAMP VALVE FOR AUTOMATIC TRAIN-CONTROL APPARATUS.

Application filed May 1, 1923. Serial No. 635,897.

To all whom it may concern:

Be it known that I, DAVID J. BISSELL, Jr., a citizen of the United States, and resident of Spokane, in the county of Spokane and 5 State of Washington, have invented certain new and useful Improvements in Ramp Valves for Automatic Train-Control Apparatus, of which the following is a specification.

- 10 My invention relates to automatic train control apparatus of the type including a ramp valve or valves effective upon actuation thereof by suitable track mechanism to cause an automatic reduction of pressure in the 15 ordinary train air brake system with consequent setting of the brakes and stopping of the train under certain predetermined conditions, as for instance, in the event the train should attempt to enter an occupied block.
- 20 More particularly my invention relates to an improved ramp valve and means for automatically controlling its operation, as disclosed, but not claimed *per se* in my copending application serially numbered 25 635,895.

In the accompanying drawings which are illustrative of my improved ramp valve in its preferred form, and wherein like characters of reference denote corresponding 30 parts in the different views,

Figure 1 is a vertical section through my improved ramp valve and its automatic control means, showing the relation of these 35 parts relatively and with respect to a ramp device for actuating the same;

Figure 2, an elevation of one end of the ramp valve;

Figure 3, an elevation of the other end of the ramp valve;

40 Figure 4, an enlarged transverse section showing the ramp valve actuated to train stopping position;

Figure 5, a longitudinal section through the ramp valve; and

45 Figure 6, a detail sectional view through the ramp valve showing the bleed opening therein.

Referring now to the drawings by numbers, it will be observed that my improved 50 ramp valve, which is adapted to be mounted at any suitable point on a locomotive, consists essentially of a casing 10 provided with a bore 11 within which is rotatably mounted a plug 12. Preferably the bore

11 and plug 12 are tapered whereby a tight fit of the latter within the former is assured and whereby wear may be compensated, plug 12 being held within said bore 11 in any preferred manner as for instance by means of the removable cap illustrated at 13.

Formed in the casing 10 are three evenly spaced ports 14, 15 and 16 that are disposed in the same transverse plane with a pair of relatively communicating ports 17 and 18 formed in the plug 12, said ports 17, 18 being so spaced that when plug 12 is in one predetermined rotated position, they align, respectively, with ports 15, 16, while in another predetermined rotated position of the plug they align, respectively, with ports 14, 15 and port 16 is blanked. The plug 12 preferably is provided with a tapered bore within which is disposed a hollow sleeve 19 as and for the purpose disclosed in my copending application previously referred to, but as the provision of sleeve 19 is not new with me and is not essential, it need not here be considered in detail. The plug also is provided with a port 20 that is of limited depth and elongated in the direction of the axis of the plug, so that when ports 17, 18 are aligned, respectively, with ports 15, 16, port 14 is placed in communication with a small bleed opening 21 formed in the casing 10 and opening to the atmosphere.

The means for rotating plug 12 consists of a depending ramp engageable shoe including a pair of arms 22, 23 connected together by a cross piece or pieces 24. One of these arms, 22, is non-rotatably connected with a projecting end of the plug 12, while the other arm, 23, is rotatably journaled on a stud 25 projecting from the casing 10, said stud having secured thereto a double arm spring 26, the ends of which are connected with arm 23 of the shoe, so as to hold said shoe normally in a vertical position with ports 17, 18 aligned, respectively, with ports 15, 16, or, if desired, this purpose may be accomplished in any other desired or preferred manner, the only essential being that means be provided, the tendency of which is to return the shoe automatically to normal vertical position following its angular movement and consequent rotation of plug 12 from any cause.

Carried by the lower ends of arms 22, 23

is a roller 27 that is adapted to contact with a ramp to swing the shoe and as a consequence rotate the plug 12.

Associated with said ramp valve is a latch device to retain the shoe in an upwardly swung position against the force of spring 26 following actuation of the shoe by a ramp device. This latch device consists of a pin 28 carrying a disk 29 that is slideable within a bore 30 in the casing 10, said pin, at its inner end, extending through a reduced portion of said bore into contact with the outer surface of plug 12, and at its outer end being surrounded by an expansion coil spring 31 that reacts from a cap 32 threaded on the casing in enclosing relation to said bore and pin, against disk 29 to urge the pin inwardly into contact with the plug. In the plug is formed a recess 33 into which the inner end of the pin is projected by said spring to latch the plug against rotative movement when the shoe has been swung to align ports 17, 18 with ports 14, 15.

Communicating with the inner end of the bore 30 is a pipe 34 by means of which air under pressure may be introduced against the inner face of disk 29 to force the same outwardly and thus withdraw pin 28 from recess 33 to unlatch the plug 12 whereby the same may be returned automatically to its normal position by spring 26.

A slide valve is associated with said ramp valve to control the air supply to the bore 30 for releasing the latch device, said slide valve being located a considerable distance either forwardly or rearwardly of the ramp valve, depending upon whether the latter is intended for controlling forward or backward movements of a train, this for a purpose that will later appear.

The slide valve consists of a casing 35 within which is vertically movable a block 36, one side of which is provided with an elongated recess 37. This block has secured thereto the upper end of a rod 38 that depends through a suitable brace or fixed support 39 and at its lower end is provided with a ramp engageable roller 40. On said rod is a collar 41 and bearing downwardly on this collar is a coil spring 42 that urges said rod downward and as a consequence holds the block normally at its limit of downward movement within the casing 35, in which position of the block recess 37 communicates at one end with a port 43 in the casing to which pipe 34 is connected, and at its other end communicates with a port 44 in the casing opening 60 to the atmosphere. Thus the bore 30 of the ramp valve is vented normally and subject only to atmospheric pressure, so that the inward projecting influence of spring 31 against the pin 28 is unresisted.

Leading into the casing 35 is a pipe 45

by means of which the casing is provided with a constant supply of air under pressure. Consequently, whenever the block 36 is raised sufficiently to uncover port 43, port 44 simultaneously is blanked and air is admitted from the casing into pipe 34 to retract the pin 28 from recess 33 and thus release the latch as aforementioned. The rod 38 has only a limited amount of upward movement as determined by a suitable stop thereon engageable with the fixed support 39, and when it is at the limit of its upward movement, roller 40 is disposed below the roller 27 of the ramp valve when the latter is in its normal running position, this for a purpose that will later appear.

The ramp device consists of a suitable casing 46 within which is arranged suitable mechanism for operating the ramp rails 47, 48, whereby, if the track is clear, said ramp rails, while remaining normally elevated, are capable of being depressed by slight force and consequently are ineffective to actuate the ramp valve, while on the other hand, if the track is blocked and said ramp rails are depressed, they immediately return to the elevated position indicated in the drawings and their depression is resisted so that they are effective to actuate the ramp valve. Leading to said ramp device is an elongated, gradually inclined approach rail 49.

My improved ramp valve as described in the foregoing may be connected with the usual train line pipe and with the supply from the usual engineer's valve in various manners, but for convenience I have shown the same connected substantially as indicated in my copending application 635,895 previously referred to; that is, port 16 has connected therewith a supply pipe 50 and port 15 is connected by a pipe 51 with the train line pipe 52, while port 14 is connected by a pipe 53 with a suitable speed control valve or mechanism as indicated at 54 and also with a suitable valve 55 that places pipe 53 normally in communication with the atmosphere, but which may be closed manually to cause all air within said pipe 53 to flow to valve 54.

In view of the foregoing, the operation of my improved ramp valve is apparent and as follows:

Upon movement of the train in a direction to pass over the ramp device, roller 40 contacts with and rides up the approach rail 49 until rod 38 raises block 36 sufficiently to uncover port 43 and simultaneously blank port 44. This admits air into bore 30, but if the shoe and plug of the ramp valve are in normal running position the effect of such admission of air is nil. On the other hand, if the shoe and plug of the ramp valve are in the position shown in Figure 130

4, the latch pin 28 will be retracted from recess 33 and spring 26 then will act to move the plug and shoe to normal running position. Upon continued movement of the 5 train, roller 27 on the shoe of the ramp valve contacts with ramp rails 47, 48, but if the track is clear, downward movement of these rails is unresisted and consequently no actuation of the ramp valve will 10 result. If, on the other hand, the track is blocked and downward movement of the ramp rails is resisted, the shoe of the ramp valve will be swung to the position of Figure 4 and as a consequence, the supply will 15 be cut off and the train line exhausted through valve 55, thus causing the brakes to be applied to bring the train to an automatic stop. If the engineer is alert, he may close valve 55, so that train line pressure 20 will be exhausted through valve 54 only in the event the train exceeds a predetermined low rate of speed. Accordingly the train may proceed within such predetermined low rate of speed until the next ramp 25 device is encountered and if the track then is clear actuation of the latch mechanism will release the shoe and permit the spring 26 to return the parts of the ramp valve to normal running position, whereupon the 30 train may proceed at increased speed as is apparent. On the other hand, so long as the track remains blocked, succeeding ramp devices will serve to maintain the ramp valve in the position of Figure 4 and the 35 speed of the train thus will be maintained at or below the predetermined low rate permitted by valve 54.

By the provision of port 20 and bleed opening 21, the air pressure in pipe 53, 40 following actuation of the ramp valve, is vented to the atmosphere.

From the foregoing description considered in connection with the accompanying drawings, it is believed that the construction, operation and advantages of my present improvement will be fully understood. It is desired to point out, however, that various changes and desirable additions may be made in and to the arrangements illustrated within the spirit and scope of my invention as defined in the appended claims.

I claim:

1. In automatic train control apparatus, the combination with the train pipe and the 55 fluid pressure supply pipe of an ordinary air brake system, of a ramp operable valve having a normal position establishing communication therethrough between the pressure supply pipe and the train pipe and movable to another position to deny communication therethrough between the supply pipe and the train line pipe and simultaneously vent the train line pipe, and automatically releasable means to hold said valve 60 in the latter position.

2. In automatic train control apparatus, the combination with the train pipe and the fluid pressure supply pipe of an ordinary air brake system, of a ramp operable valve having a normal position establishing communication therethrough between the pressure supply pipe and the train line pipe and 70 simultaneously vent the train line pipe, means constantly urging said valve to a normal position, and an automatically releasable device to hold said valve in a train pipe venting position against the influence of 75 said means.

3. In automatic train control apparatus, the combination with the train pipe and the fluid pressure supply pipe of an ordinary air brake system, of a ramp operable valve 85 having a normal position establishing communication therethrough between the pressure supply pipe and the train pipe and movable to another position to deny communication therethrough between the supply pipe and the train line pipe and simultaneously vent the train line pipe, and automatically operable fluid pressure releasable means to hold said valve in the latter position.

4. In automatic train control apparatus, the combination with the train pipe and the fluid pressure supply pipe of an ordinary air brake system, of a ramp operable valve having a normal position establishing communication 100 therethrough between the pressure supply pipe and the train pipe and movable to another position to deny communication therethrough between the supply pipe and the train line pipe and simultaneously vent the train line pipe, a latch device engageable with the valve to hold the same in the latter position, and fluid pressure means including an automatically operable valve to release said latch device.

5. In automatic train control apparatus, the combination with the train pipe and the fluid pressure supply pipe of an ordinary air brake system, of a ramp operable valve having a normal position establishing communication 115 therethrough between the pressure supply pipe and the train pipe and movable to another position to deny communication therethrough between the supply pipe and the train line pipe and simultaneously vent the train line pipe, a latch device engageable with the valve to hold the same in the latter position, and ramp operable means to release said latch device.

6. In automatic train control apparatus, the combination with the train pipe and the fluid pressure supply pipe of an ordinary air brake system, of a ramp operable valve having a normal position establishing communication 125 therethrough between the pressure supply pipe and the train line pipe and simultaneously vent the train line pipe, and automatically releasable means to hold said valve in the latter position.

- sure supply pipe and the train pipe and movable to another position to deny communication therethrough between the supply pipe and the train line pipe and simultaneously vent the train line pipe, a latch device engageable with the valve to hold the same in the latter position, and fluid pressure means including a second ramp operable valve to release said latch device.
7. In automatic train control apparatus, train carried mechanism comprising, in combination with the train pipe and fluid pressure supply pipe of an ordinary air brake system, a valve having a normal position establishing communication between said pressure supply pipe and said train pipe and movable to another position to deny communication between said pressure supply pipe and said train pipe and simultaneously vent the train pipe, a device to hold said valve in train pipe venting position, and means controlled by train movements to effect release of said device to permit said valve to move to normal position.
8. In automatic train control apparatus, the combination with the train pipe and the fluid pressure supply pipe of an ordinary air brake system, of a valve having a normal position establishing communication between the pressure supply pipe and the train pipe 30 and movable to another position to deny communication between the supply pipe and the train pipe and to simultaneously vent the train pipe, a releasable device to hold said valve in the latter position, fluid pressure 35 operated means for effecting release of said device to permit the valve to move to normal position, and means for automatically operating said fluid pressure means under predetermined conditions.
9. In automatic train control apparatus, the combination with the train pipe and the fluid pressure supply pipe of an ordinary air brake system, of a valve having a normal position establishing communication between 40 said fluid pressure supply pipe and said train pipe and movable to another position to deny communication between the supply pipe and the train pipe and to simultaneously vent the train pipe, and a releasable device to hold said valve in the latter position, said device and said valve being adapted for automatic actuation by a common operator.
- In testimony whereof I hereunto affix my 55 signature.

DAVID J. BISSELL, JR.
